UNITED STATES PATENT OFFICE.

JOHN S. WHITE, OF WOODLYNNE, NEW JERSEY.

SHIP-WINDOW.

1,171,573.

Specification of Letters Patent. Patented Feb. 15, 1916.

Application filed October 3, 1914. Serial No. 864,902.

To all whom it may concern:

Be it known that I, JOHN S. WHITE, of Woodlynne, in the county of Camden and State of New Jersey, have invented certain new and useful Improvements in Ship-Windows, whereof the following is a specification, reference being had to the accompanying drawings.

Ship windows call for the employment of a number of alternative sashes or closures. Thus, it is desirable that there shall be provided for such windows in addition to the clear glass sash or double sash, a heavier storm sash, a sliding blind or shutter, and an insect screen. The problem of the stowage of so many sashes in the limited space afforded by marine construction, is the one to which this invention is directed. One or more of the sashes may simply be made removable, but as a rule it is necessary to stow two or three of the sashes within the wall space. Hitherto this has been accomplished by the use of a pocket below the window aperture. The objection to this is that it provides a space capable of receiving water. According to my present invention I provide a space directly over the window aperture and employ it for the stowage of two or three of the sashes employed.

It is a further object of my invention to render all of the sashes light enough to be handled and adjusted without the employment of counterweights.

Further details of my invention will be referred to in the specification and claims.

In the accompanying drawings, Figure I, is a vertical sectional view of a ship window and surrounding parts embodying my invention, the window being provided with a screen sash, storm sash, glass sash and shutter sash. Figs. II, and III, are detail sectional views showing the arrangement of my anti-rattler strips on either side of the plain sash.

Referring to Fig. I, the window there shown is set in a wall formed of an outer partition 2, and an inner partition 3, with provision of the space 4, between the two, above the window, forming a convenient pocket for the stowage of such sashes protecting the window as are not removably interposed in the aperture. The sill 5, frames the bottom of the window aperture. Run-ways for the sashes are formed at the sides of the window aperture, by properly spaced parting beads in the form of the anti-

rattler strips 6, and 10, which are preferably sheet brass bent to form a three-sided trough. The central side is pierced by a series of diagonal slots 7, succeeding each other at 60 intervals, short enough to enable a sash to be set at any desired height. The side rails of the sashes which run against these metal parting beads are faced with metal strips 39 (see Fig. III).

Sliding in the run-way formed between the inner partition and the strip 6, is a sash 8, provided with fixed slats 9. Sliding in the run-way between the strips 6, and 10, is the sash 11, with a glass pane 12. Sliding in the run-way formed between the outer partition and the strip 10, is the storm sash 16, which is provided near the bottom with a small heavy glass pane 13. A similar small pane 14, is set in the upper part of this storm sash which otherwise is solid. The outer partition has a small translucent but not transparent pane 15, set in it, as a point corresponding to the position of the lower small pane 13, when the storm sash is raised. When the shutter sash, the plain glass sash, or the storm sash are raised, they are stowed within the space 4, above the window between the partitions. The height of the shutter sash is such that when the sash is lowered, the top will come sufficiently below the partition wall 3, to leave a space corresponding to the opening 15, and permit the passage of sufficient light. Furthermore, the passage of light is not interfered with by the storm sash in either position, for when in the lower position, its top is also below opening 15, and when raised pane 13, correspond with pane 15, as shown in Fig. I.

A sash 20, provided with a wire net insect screen 21, is removably inserted within the window aperture outside of the sashes, which have been mentioned. For this purpose, the window aperture is provided at the top with the overhanging strip 22, beneath which the screen sash is set. At the bottom the screen is secured by the sliding dowel pin 25, the end of which enters an appropriate socket in the sill.

The glass sash 11, has attached to its inner face a metal case 28, provided with a latch or pin 29, which is withdrawn by pressure upon the handles 30. The pin 29, is normally spring pressed so as to shoot into one of the slots in the anti-rattler strip to which its end is opposed. When entering one of these slots, the weight of the sash

forces it against the strip 10, on the opposite side, thereby creating tension between the two which effectually prevents all rattling. The same device is provided for the storm sash, and if desired also for the shutter sash, although here it is less necessary as this latter sash is rarely placed other than in fully open or fully closed position.

A further advantage of my invention is in the comparatively small size of the sashes thus provided, whereby they are rendered of less weight than those which have hitherto been employed for similar purposes. It is desirable that such sashes should be of small weight, since if they are very heavy, it is necessary to provide balancing weights or spring tape balances which are very objectionable in marine architecture.

Having thus described my invention, I claim:

1. In a ship window, the combination of the window aperture formed in a wall having inner and outer partitions; a space between said partitions above the window aperture for stowage of the sashes, the window aperture being of greater height in the inner partition than the outer partition, a sash stowing away in said storage space of a height only sufficient to close the aperture in the outer partition, whereby a clear space is provided between the top of the aperture in the inner partition, and the top of the sash, and a small pane inserted in the outer partition in position to permit light to pass through the above mentioned clear space.

2. In a ship window, the combination of a window aperture having inner and outer partitions, a space between said partitions

above the window aperture for stowage of sashes, the window aperture being of greater height in the inner partition than the outer partition, a small pane inserted in the outer partition below the lower end of the inner partition, a storm sash stowing away in said stowage space also provided with a small pane which registers with the first mentioned small pane when the storm sash is in its raised position.

3. In a ship window, the combination of the window aperture formed in a wall having inner and outer partitions; a space between said partitions above the window aperture for stowage of the sashes, the window aperture being of greater height in the inner partition than the outer partition; a sash stowing away in said stowage space of a height only sufficient to close the aperture in the outer partition, whereby a clear space is provided between the top of the aperture in the inner partition and the top of the sash, a small pane inserted in the outer partition in position to permit light to pass through the above mentioned clear space, a storm sash stowing above the window and also provided with small panes, the lower of said panes corresponding in position to the first mentioned small pane when the storm sash is in the raised position.

In testimony whereof, I have hereunto signed my name, at Philadelphia, Pennsylvania, this first day of October 1914.

JOHN S. WHITE.
